DESIGN FOR A COOK STOVE.

WILLIAM RESOR, OF CINCINNATI, OHIO.

Design No. 2,520, dated December 4, 1866.

SPECIFICATION.

TO ALL WHOM IT MAY CONCERN:

Be it known that I, WILLIAM RESOR, of Cincinnati, in the county of Hamilton, and State of Ohio, have invented a new Design for a Cooking Stove; which design is represented in the accompanying photograph, which forms a part of this specification.

I claim, and desire to secure by Letters Patent—

The design for a cooking stove, substantially as represented in the accompanying photograph.

In testimony of which invention I hereunto set my hand.

WM. RESOR.
